UNITED STATES PATENT OFFICE.

SOLOMON SLOMKA, OF NEW YORK, N. Y.

COMBINED SCHOOL BAG AND WRITING PAD.

Application filed October 20, 1924. Serial No. 744,587.

This invention relates to a school bag or brief case and has special reference to the provision of a combined school bag and desk or writing pad.

5 A prime object of my present invention comprehends the provision of a brief case or school bag constructed and designed to serve when opened as a writing or desk pad, the school bag having a compartment section, a 10 desk pad section and a pencil rack or holder section coordinated and related so as to produce an attractive and highly serviceable arrangement of the parts.

15 A further prime object of my present invention relates to the provision of a school bag or brief case embodying a novel pencil holder or rack combined and associated with the school bag handle so as to form a support therefor and a stiffening or reinforcing means 20 for the body of the bag.

To the accomplishment of the foregoing and such other objects as may hereinafter appear, my invention consists in the elements and their relation one to the other as herein- 25 after particularly described and sought to be defined in the claims; reference being had to the accompanying drawings which show a preferred embodiment of my invention and in which:

30 Figure 1 is a perspective view of my improved school bag and writing pad showing the same opened for use as a desk or writing pad;

Figure 2 is a fragmentary view shown on an enlarged scale taken in cross-section on 35 the line 2-2 of Figure 1;

Figure 3 is an end view of the brief case or school bag, with the parts moved to closed position;

Figure 4 is a perspective view of the same 40 shown on a reduced scale; and

Figure 5 is a fragmentary view in perspective showing the combined school bag handle and pencil rack.

As heretofore stated, one of the prime 45 desiderata of the present invention relates to the provision of a brief case or school bag constructed and designed to serve when opened as a writing desk or pad, the school bag having compartment, desk pad and pencil holder sections coordinated in a manner 50 to produce an attractive and highly serviceable arrangement of parts. More specifically and having reference to the drawings, the combined school bag and writing pad of my 55 present invention comprises a compartment

section generally designated as *a*, a writing or desk pad section generally designated as *b* joined by an intermediate flexible fold section or portion *c*, the pad section *b* being movable about the fold section *c* into overlying relation with the compartment section *a* when the parts are moved to closed position, the said sections being movable when opened so as to lie generally in a single plane as shown 60 in Figure 1 of the drawings when the school bag is to serve as a writing or desk pad.

The compartment, pad and intermediate sections may be made of any suitable material, such as leather or the like, the compartment section *a* being provided with one or more expansible compartments or pockets 10 opening at or adjacent to the fold portion *c*; and the pad section *b* being preferably provided with a plurality of corner pockets 11, 11 75 of the usual triangular shape for receiving one or more blotters 12. The compartment and pad sections may be provided with the usual hasp or mating lock sections 13 and 14 to lock the parts as shown in Figure 4 of the 80 drawings when the sections are moved to closed or overlying position.

In the combined school bag and writing pad of my invention, the intermediate or fold portion *c* forms the carrying means for 85 the bag sections and the said intermediate fold portion is provided with a pencil rack or holder generally designated as *d*, the said pencil rack or holder being arranged interiorly of the fold portion and being associated with the school bag handle 15, the latter arranged exteriorly of the fold portion, so as to form a supporting means for the handle and a stiffening or reinforcing means for the fold portion *c* functioning to give body to 90 and to maintain the shape of the school bag or brief case.

In the preferred construction the pencil holder *d* comprises a transverse metal strip 16 having upturned end flanges 17 and 18 (see particularly Figures 1 and 5), the said upturned end flanges being provided with a plurality of concave, or V-shaped, notches 19, 19 constructed to receive or seat a plurality of pencils and pen holders, as clearly shown 100 in Figures 1 and 2 of the drawings. The handle 15 is supported by and secured to the metal strip 16 of the pencil holder by means of the fastening elements 20 and 21, each of which, as is clearly shown in the drawings, 110 comprises a yoke member looped about an end of the bag handle 15, the opposite ends of

the yoke member being inserted through an aperture in the metal strip 16 and then turned down into engagement with the under side of the latter, as will be clearly apparent from a consideration of Figures 1, 2 and 5 of the drawings. The pencil holder may also be provided with an intermediate support 22 secured to the transverse strip 16. It is desirable to construct the pencil holder or rack so that the pencils may be carried by the holder against displacement when the bag is closed, as shown in Figure 3 of the drawings, and so that the pencils may be readily removed from and replaced on the holder during writing use, as shown in Figure 1 of the drawings. To these ends I prefer to provide a releasable element 23 which for convenience may comprise a resilient or coiled spring yoke member fastened at its opposite ends to the intermediate support 22 and movable to embrace the pencils and pen holders *pp*, as shown in Figures 2 and 3 of the drawings, and releasable as shown in Figure 1 of the drawings to permit ready removal of the pencils from the holder.

With the provision of this combined handle and pencil holder or rack, it will be seen that all stiffening and reinforcing strips heretofore used in brief case construction may be eliminated, the pencil rack forming a suitable and strong support for the handle and reinforcing or stiffening strip for the bag body.

The manner of making and using the combined school bag and writing pad of my invention and the advantages thereof will in the main be fully apparent from the above detailed description thereof. It will be further apparent that with the construction providing a convenient and serviceable arrangement of parts is produced both when the bag is employed for carrying books, stationery and the like and when the same is employed as a writing support or desk device. When the parts are moved to open position the pencil holder occupies a position intermediate the compartment section and the writing pad or support and is located at the head or top of the latter so as to be related therewith for ready accessibility by the writer. Moreover with the arrangement provided and with the expandible pocket opening at the fold section a maximum of convenience is afforded, the compartment being readily reached for removal of books, stationery or the like during writing use of the device, as is exemplified in Figure 1 of the drawings. Furthermore, by the provision of the combined pencil rack and brief case handle, the former serving as a support and reinforcing means for the latter, stiffening strips commonly employed in brief case structures are entirely eliminated and an inexpensive pencil rack or holder capable of manufacture and assembly at low cost is afforded. Also with the

parts relatively arranged as shown and described the sections may be moved to closed condition without interference, and the normal carrying capacity of the bag is retained or maintained.

While I have shown and described my invention in the preferred form, it will be further apparent that numerous changes and modifications may be made therein without departing from the spirit of the invention, as defined in the following claims.

I claim:

1. A combined school bag and pad comprising a compartment section having an expandible pocket adapted for receiving books or the like, a pad section adapted to form a writing support, an intermediate fold portion joining the compartment and pad sections, the said sections being foldable about the fold portion into overlying relation, a handle secured exteriorly to the fold portion, and a pencil rack or holder secured interiorly to the fold portion, the pencil holder having a relatively stiff portion constituting a transverse stiffening or reinforcing means for the fold portion and bag.

2. A combined school bag and pad comprising a compartment section having an expandible pocket adapted for receiving books or the like, a pad section adapted to form a writing support, an intermediate fold portion joining the compartment and pad sections, the said sections being foldable about the fold portion into overlying relation, a pencil rack or holder secured interiorly to the fold portion, and a handle for the bag secured to the pencil holder and arranged exteriorly of the fold portion, the pencil holder forming a support for the handle and a stiffening or reinforcing means for the fold portion and bag.

3. In a school bag or the like, a fold portion joining relatively movable sections, a handle for the bag secured exteriorly to the fold portion, and a pencil rack or holder secured interiorly to the fold portion, the pencil holder having a part constituting a transverse stiffening or reinforcing means for the fold portion and bag.

4. In a school bag or the like, a fold portion joining relatively movable sections, a pencil rack or holder secured interiorly to the fold portion, and a handle for the bag secured to the pencil holder and arranged exteriorly of the fold portion, the pencil holder forming a support for the handle and a stiffening or reinforcing means for the fold portion and bag.

5. In a school bag or the like, a fold portion joining relatively movable sections, a pencil holder or rack secured interiorly to said fold portion, a handle for the bag secured exteriorly to said fold portion, the pencil holder having means associated with the handle of the bag to form a stiffening or rein-

forcing means for the latter and for the fold portion, the said pencil holder including means for holding pencils or the like against displacement releasable to permit pencils to be readily removed from or replaced on the holder during writing use.

6. In a school bag or the like, a fold portion joining relatively movable sections, a pencil rack or holder arranged interiorly of said fold portion, a handle for the bag arranged exteriorly of said fold portion and secured to said holder, the holder forming a reinforcing or stiffening means for the fold portion and a support for the handle, the said pencil rack comprising a transverse metal

strip provided with upturned end flange portions having means for seating or receiving pencils or the like, and a resilient yoke element connected to said holder and operative for embracing pencils or the like to hold same against displacement, the said resilient yoke member being movable into an inoperative position to permit the pencils to be readily removed from or replaced on the holder during writing use.

Signed at New York, in the county of New York and State of New York, this 16th day of October A. D. 1924.

SOLOMON SLOMKA.
